BY Walter C. Ross
his ATTORNEY.

UNITED STATES PATENT OFFICE

JOSEPH N. FOUNTAIN, OF WESTFIELD, MASSACHUSETTS, ASSIGNOR TO OLD COLONY ENVELOPE COMPANY, OF WESTFIELD, MASSACHUSETTS, A CORPORATION OF MASSACHUSETTS

SHEET-FEEDING APPARATUS

Original application filed February 6, 1928, Serial No. 252,276. Divided and this application filed February 9, 1929. Serial No. 338,852.

This invention relates to improvements in apparatus for feeding blanks or sheets and the application is a division of an application filed by me on February 6, 1928, bearing Serial No. 252,276.

The invention is adapted for broad application wherever it is desired to feed blanks or sheets and is particularly useful where it is desired to feed the same to envelope machinery, printing apparatus and the like.

The object of the invention is the provision of an apparatus which is simple in construction and efficient in operation and the novel features thereof to be described in the 15 form at present preferred are shown in the accompanying drawings in which:

Fig. 1 is an elevational view of an apparatus embodying the features of the invention.

20 Fig. 2 is a sectional elevational view taken on the line 2—2 of Fig. 1 looking to the left.

Fig. 3 is a detail elevational view of a suction picker forming part of the invention, and

25 Fig. 4 is a sectional elevational view taken on the line 4—4 of Fig. 1.

Referring to the drawings the invention will now be described in detail.

The apparatus will be described with particular reference to the feeding of such sheets or blanks as are to be received by an envelope machine or a printing press. While the apparatus is adapted for broad application it will be understood that the term blank as 30 used is not to be construed in a limited way as such a term may include envelope blanks, liners, blanks of all kinds, patches or whatever it may be desired to feed by means of the apparatus.

35 Fig. 40 In the drawings 2 and 4 represent side frames for supporting the apparatus. These may be a part of the machine with which the apparatus is used or of course may be separate therefrom as is desired.

40 A support or table 6 is shown which may support a pile of blanks B in stacked relation so that an uppermost blank is presented for removal from the stack. A hold down device or devices in the form of a finger 10 is 45 arranged to bear on the uppermost blank at

the forward side thereof and prevent a displacement thereof. This may be suitably supported by a cross bar 12. The support may be elevated in steps in the usual manner so that the uppermost blank is carried against the 55 hold down while a rear hold down 14 may be provided at the rear end of the stack.

A shaft 24 is rotatably in the side frame 2 while a hollow non-rotatable shaft 26 in axial alignment therewith is fixed in the side frame

60 4. The shaft 24 may be driven by means of a pulley in the ordinary way or suitably connected by gears or the like to the machine with which the apparatus is used. A shaft 30 journalled in the side frames 2 and 4 may 65 be gear connected to the shaft 24 so that they operate in proper timed relation. The shafts have coating rolls 32 and 34 fixed thereto which are adapted as they rotate to engage a blank and feed it forwardly when it is delivered thereto by the apparatus now to be described.

70 A hollow blank lifter 40 having a pair of depending arm portions 42 and 43 has a portion 41 intermediate said arms which is journalled in the disc 32 near the periphery thereof and an end portion 44 journalled in a disc 46 fixed to the end of said shaft 24.

75 As the roll or disc 32 rotates the lifter journalled therein is carried thereby and held 80 in a generally radial position with respect thereto by means of the following.

An extension 48 of the lifter 40 carries a roll 50 which rides on a cam surface 52 formed in a circular hub 54 of the side frame 85 2. A spring 56 having one end connected to a projection 58 of the lifter and its other end to a pin 60 on the rear face of the disc 46 tends to swing the lifter relative to the disc 46 and roll 32 in a counter-clockwise direction so that the roll 50 will engage with and follow the cam surface.

80 As the roll 32 rotates counter-clockwise and carries the blank lifter therewith the arms 42 and 43 of the lifter extend in the 90 radial direction described so that the ends thereof bring up against the uppermost blank of the stack as in Fig. 2. A curved or raised portion 64 of the cam surface, shown in dotted lines in Fig. 2, and against which the 95

roll 50 contacts is arranged to move the lifter clockwise with respect to the roll 32 and disc 46 and raise the ends thereof as shown by dotted lines 42A. The lifter being hollow and connected to suction means the uppermost blank will be elevated and its forward end pulled from beneath the hold down 10. The lifter being thus elevated and rotated for the particular purpose it is subsequently allowed to swing towards its normal position by a surface 66 of the cam as is shown.

As it swings back to its normal position and being rotated by the roll 32 and disc 42 the end thereof assumes such a position as 15 will carry the blank between the rolls 32 and 34, see the dotted line position 42^b in Fig. 2.

The non-rotatable shaft 26 being hollow it may be connected by means of a pipe 70 to a suction device such as a pump (not shown) 20 or the like. A disc 78 fixed to the inner end of the shaft 26 has a central opening 80 to allow communication with the hollow shaft and has secured thereto a plate 82. This plate is also provided with a central axial 25 opening 84 and a cutaway portion 86 in communication therewith. The cutaway portion is in the path of the end 44 of the lifter as it is rotated and is arranged so that the lifter is in communication with suction while it 30 travels past the cutaway and through the angle represented by α in Fig. 4. The angle and cutaway portion are preferably arranged so that as the arm arrives at the position shown in Fig. 2 the blank will be drawn 35 against the end of the arms 42 and 44 by suction and held there until the arms reached the dotted line position 42^b in Fig. 2 where the blank is received by the coacting rolls 32 and 34 and released by the lifter.

40 In operation the rolls 32 and 34 are rotated in the direction of the arrows. The oscillatable lifter is maintained in a radial position by being held against the cam by the spring. As the lifter engages the uppermost 45 sheet of a stack it is in communication with the source suction so as to suctionally engage said blank. When thus engaged the lifter is caused to swing rearwardly with respect to the roll 32 or clockwise so that the blank is 50 lifted to free the end thereof.

In position the lifter is carried forwardly so as to feed the blank to the rolls and during the latter part of its movement or directly thereafter the cam surface permits the 55 spring to return the lifter to its normal radial position.

Having described the invention in its present preferred form, what I desire to claim and secure by Letters Patent is:

50 1. Blank feeding apparatus comprising in combination, a support for a stack of blanks, a pair of rolls for receiving blanks, a suction lifter oscillatable on one of said rolls for suctionally engaging a blank and means for swinging said lifter rearwardly with respect

to said roll after it has engaged said blank so as to lift the same and deliver it between said rolls as it is rotated thereby.

2. Blank feeding apparatus comprising in combination, a support for a stack of blanks, 70 a pair of rolls for receiving blanks, a suction lifter oscillatable on one of said rolls for suctionally engaging a blank and means for swinging said lifter rearwardly with respect to said roll after it has engaged said blank so as to lift the same and deliver it between 75 said rolls as it is rotated thereby and means for controlling the application of suction to the blank by the lifter.

3. Blank feeding apparatus comprising in combination, a support for a stack of blanks, 80 a pair of coacting rolls for receiving blanks, a suction lifter oscillatable on one of said rolls for suctionally engaging a blank, a hold down for bearing on the uppermost blank of a stack, means for oscillating said lifter on said roll as it is rotated thereby for lifting a blank from said stack and delivering the same to said rolls and means for controlling the application of suction to the blank by 85 the suction lifter.

4. Blank feeding apparatus comprising in combination, a non-rotatable hollow shaft for connecting to a source of suction, a rotatable shaft in axial alignment therewith, a support for a stack of blanks, a pair of blank receiving rolls, a suction lifter pivoted on one of said rolls and means for maintaining it in a normal radial position as it is rotated by said roll so that its end will engage a blank on said stack, means for connecting said lifter to said hollow shaft as it engages a blank, means for moving said lifter angularly of said roll so that a blank engaged thereby is delivered to said rolls and for returning it to said normal position after said delivery. 100

5. Blank feeding apparatus comprising in combination, a pair of rotatable coacting blank receiving rolls, a support for a stack of blanks, a suction lifter pivoted on one of said rolls having an extension for engaging a blank, means for maintaining said lifter in a normal radial blank engaging position, means for moving said lifter so that its extension is moved rearwardly with respect to said roll as it engages a blank and for returning to normal position whereby a blank may be lifted from a stack and delivered to said rolls. 110

6. Blank feeding apparatus comprising in combination, a pair of rotatable coacting blank receiving rolls, a support for a stack of blanks, a suction lifter pivoted on one of said rolls and normally extending radially thereof whereby an end thereof may engage a blank of a stack, means for moving said lifter angularly with respect to said roll as it engages a blank so that said blank may be elevated above said stack and delivered to said rolls and for returning the same to its normal 120 position. 125

radial position and means for controlling the application of suction to the blank by the lifter.

7. Blank feeding apparatus comprising in combination, a pair of rotatable coacting blank receiving rolls, a support for a stack of blanks, a suction lifter pivoted on one of said rolls at one side of its axis of rotation, means for maintaining said lifter in a normal radial position as it is rotated by said roll whereby its end will engage a blank, means for swinging said lifter relative to said roll as it engages a blank so that its blank engaging position moves in the opposite direction to that of the movement of the roll whereby the blank is elevated and delivered to said rolls and means for returning said lifter to its normal radial position.

8. Blank feeding apparatus comprising in combination, a support for a stack of blanks, a pair of coacting rotatable rolls for receiving blanks, a suction lifter on one of said rolls for suctionally engaging a blank on said support, which is arranged for swinging movements on said roll and means for operating said lifter on said roll in one direction for engaging a blank and for swinging it in another direction to deliver said blank between said rolls.

9. Blank feeding apparatus comprising in combination, a support for a stack of blanks, a pair of coacting rotatable rolls for receiving blanks, a suction lifter on one of said rolls for suctionally engaging a blank on said support, which is arranged for swinging movements on said roll and means for operating said lifter on said roll in one direction for engaging a blank and for swinging it in another direction to deliver said blank between said rolls, the said lifter and operating means being operable during the rotation of said rolls.

10. Blank feeding apparatus comprising in combination, a support, shafts rotatable therein, a support for a stack of blanks, coacting blank receiving rolls on said shafts, a suction lifter on one of said rolls for engaging a blank on said support, which is pivoted for swinging movements thereon between different radial positions and means associated with said lifter and first-named support whereby the lifter is swung as it is rotated by said roll.

JOSEPH N. FOUNTAIN.
